UNITED STATES PATENT OFFICE.

BENJAMIN JAMES HALL, OF BARNES, ENGLAND.

PHOTOGRAPHIC-PRINTING APPARATUS.

No. 882,676.

Specification of Letters Patent. Patented March 24, 1908.

Application filed June 19, 1907. Serial No. 379,690.

To all whom it may concern:

Be it known that I, BENJAMIN JAMES HALL, a subject of the King of Great Britain, and residing at Barnes, in the county of 5 Surrey, England, have invented certain new and useful Improvements in Photographic-Printing Apparatus, of which the following is a specification, such as will enable those skilled in the art to which it appertains to 10 make and use the same.

This invention relates to improvements in apparatus for photo-printing of the type in which the tracing and photo paper are passed continuously over a glass plate, the other 15 side of which is illuminated by daylight or by artificial light; and the object of my invention is to provide a contact between the sensitized paper, tracing and glass plate, thereby securing sharp definition, and at the 20 same time dispense with the traveling bands or aprons which are found so troublesome in use.

The invention is fully disclosed in the following specification, of which the accompanying 25 drawing forms a part, in which the separate parts of my improvement are designated by suitable reference characters in each of the views, and in which;—

Figure 1 is a partial elevation view of an 30 apparatus of the class specified constructed according to my invention; Fig. 2 a partial side view thereof; and, Fig. 3 a sectional side view.

In the accompanying drawing only sufficient 35 of the framework and apparatus are shown to illustrate my improvement, and in carrying my invention into effect, I employ a drum *a* which is mounted in a frame *b* of the usual form, and said drum is adapted to be 40 operated by hand or by power, but in the accompanying drawing, I have shown at *a*² a gearing connected with one end of the shaft of the drum *a* and operating in connection with a worm gear shaft *a*³ provided at one end 45 with a stepped pulley *a*⁴, and in practice, any suitable power device may be geared in connection with the stepped pulley *a*⁴ by means of a belt. The drum *a* is provided with a felt or other flexible cover *a*⁵; and placed rearwardly of the drum and supported, in practice, in the frame *b*, or in any preferred manner, is a glass plate *c* which is curved to correspond with the curve of the drum.

The glass plate *c* may be semi-cylindrical 55 in form or it may be less than the half of a cylinder in dimensions, and if less than the

half of a cylinder in dimensions wooden plates *c*² are employed to complete the half of the cylinder or the half of the circumference of the drum, and said wooden plates, 60 if employed, are also secured in the frame *b* in any desired manner and these wooden plates, when employed, serve as guides for the tracing and photographic paper as the latter is carried around by the drum. 65

In practice, the convex surface of the glass is illuminated by daylight or by artificial light in the usual manner, and when printing by artificial light economy may be effected by placing two such photo-printing apparatus 70 in juxtaposition with an electric arc lamp or lamps or other illuminating devices between them. In such cases the drums may be geared together and driven from one source or may be operated independently. 75

Placed over the top front portion of the drum is a table *d* supported by the frame *b* and over which the tracing and photographic paper are fed, in the operation of the apparatus, and directly over the central portion 80 of the drum is preferably placed a roller *e*, and the tracing and photographic paper are fed over the table *d* beneath the roller *e* from which they pass between the glass plate *c* and the drum *a*, or if the pieces *c*² of wood 85 are employed, the said tracing and photographic paper first passes beneath the top piece *c*² which also may be provided with a roller. At the bottom of the drum is placed another table *f* and the tracing and photographic paper after passing between the glass plate *c* and the drum pass out onto the table 90 *f*. The friction between the glass and the tracing paper being less than that between the drum and the said tracing and photographic paper there is no relative movement 95 between the tracing and photographic paper while in contact with the drum and glass plate, and the drum carries the tracing and photographic paper around with it as will be 100 readily understood, this operation being facilitated by the felt or other flexible cover *a*⁵ on the drum.

It will be understood that I have not shown all the details of the construction of the frame 105 nor the details of the apparatus for supporting electric or other lights when they are employed as they form no part of my invention, the latter being limited to the application of the glass plate *c* to a machine or 110 apparatus of this class as usually constructed.

Having fully described my invention, what

I claim as new and desire to secure by Letters Patent, is:—

1. In a photographic printing apparatus, a rotary drum provided with a fibrous cover, 5 and a curved glass plate mounted adjacent to one side thereof.

2. In a photographic printing apparatus, a frame, a rotatable drum mounted therein, a curved glass plate partly inclosing said 10 drum and arranged adjacent thereto, and means for feeding a flexible sheet between said plate and said drum.

3. In a photographic printing apparatus, a frame, a rotatable drum mounted therein,

a curved glass plate partly inclosing said 15 drum and arranged adjacent thereto, and means for feeding a flexible sheet between said plate and said drum, said drum being also provided with a felt or other flexible cover.

In testimony that I claim the foregoing as my invention I have signed my name in presence of the subscribing witnesses this 5th day of June, 1907.

BENJAMIN JAMES HALL.
